(Cl. D15—1)

Fig. 1.

To all whom it may concern:

Be it known that I, Gunnar G. Birkerts, a citizen of the Republic of Latvia, and a resident of Pontiac, in the county of Oakland and State of Michigan, have invented a new, original, and ornamental Design for a Chair, of which the following is a specification, reference being had to the accompanying drawings, forming part thereof, in which:

Fig. 1 is a front perspective view of a chair embodying my new design;

Fig. 2 is a side elevational view thereof;

Fig. 3 is a rear elevational view thereof; and

Fig. 4 is a top plan view of the seat portion of the

chair shown in Figs. 1, 2 and 3, with the major portion of the back thereof broken away and remaining portions of the back shown in section.

I claim:

The ornamental design for a chair, as shown and described.
